UNITED STATES PATENT OFFICE.

HARRY E. HOWARD, OF CHICAGO, ILLINOIS.

DESIGN FOR A METAL BRACKET FOR LADDERS.

SPECIFICATION forming part of Design No. 29,735, dated November 29, 1898.

Application filed October 13, 1898. Serial No. 693,456. Term of patent 7 years.

To all whom it may concern:

Be it known that I, HARRY E. HOWARD, a citizen of the United States, residing at the city of Chicago, county of Cook, and State of Illinois, have invented and produced a new and original shape or Design for a Metal Bracket for Ladders, of which the following is a specification, reference being had to the accompanying drawings, forming part thereof.

Figure 1 is a perspective view of a bracket embodying the features of my new design. Fig. 2 is a top plan view of the same, and Fig. 3 is a rear elevation.

As shown in the drawings, the leading or material features of my design for a bracket consist of a rectangular box A, having sides a , a' , and a^2 , but without top or bottom. Extending at right angles from the sides a a' , respectively, are wings B and C, the former being considerably longer than the latter. At the top of the wing B is a flange b, which extends the full length of the wing and beyond,

the extending portion being bent up at right angles to form an ear or lug b' . The wing C is also provided with a flange along its upper edge, as c, and its extended portion bent up at right angles to form an ear or lug c' .

Extending across the open side of the box A is a tongue D, which laps over onto the wing B, as shown.

The side a^2 of the box A, the tongue D, the wings B and C, and the lugs b' and c' are all perforated.

Having thus described my invention, what I claim as new, and desire to secure by Letters Patent, is—

The design for a metal bracket for ladders, substantially as herein shown and described.

In testimony whereof I affix my signature in presence of two witnesses.

HARRY E. HOWARD.
